UNITED STATES PATENT OFFICE

DELL J. LAHAY, OF CARNEY, MICHIGAN, ASSIGNEE, BY DIRECT AND MESNE ASSIGNMENTS, TO UNIVERSAL PLAYGROUND EQUIPMENT COMPANY, OF MENOMINEE, MICHIGAN, A CORPORATION OF MICHIGAN

ROUNDABOUT

Application filed February 14, 1929. Serial No. 339,840.

My invention relates to improvements in roundabouts, and it consists in the combinations, constructions, and arrangements herein described and claimed.

5 An object of my invention is to provide a roundabout which is arranged to seat several children, and which has novel means whereby the seat portion may be rotated.

A further object of my invention is to 10 provide a roundabout in which the seat portion is arranged to pivot at its center upon the base and the actuating member is pivoted to one side of the center of the base.

15 A further object of my invention is to provide a device of the type described which is simple in construction, durable, and efficient for the purpose intended.

Other objects and advantages will appear in the following specification, and the novel 20 features of the invention will be particularly pointed out in the appended claims.

My invention is illustrated in the accompanying drawings, forming part of this application, in which

25 Figure 1 is a side elevation of my device, portions thereof being broken away, and

Figure 2 is a section along the line 2—2 of Figure 1.

In carrying out my invention, I provide a 30 base 1 which has a substantially horizontally extending member 2 provided with four projections which have their outer ends secured to the transversely extending legs 3 of the base 1.

35 A disc 4 is mounted upon the base 1 at the center thereof. An eccentric shaft 5 extends through the disc 4 and has the lower end rigidly secured to the member 2. A collar 6 is disposed concentric with the shaft 5 between the member 2 and the disc 4. A supporting arm 7 is carried by the upper end of the eccentric shaft 5.

A rotating member 8 is provided with an annular seat portion 9 having inwardly extending connecting arms 10 which have their inner ends secured to a bearing support 11. Roller bearings 12 are carried by the bearing support 11 and arranged to engage with the peripheral edge of the disc 4.

50 Upwardly extending brace rods 13, which

have their lower ends secured to the connecting arms 10, have their upper ends secured to a top member 14. A pivot screw 15 is carried by the top member 14 and has its conical-shaped end received in a conical-shaped recess in the inner end of the arm 7.

An actuating member 16 is provided with an annular gripping member 17 which is connected to a sleeve 18 by means of bars 19. The sleeve 18 is disposed concentric with the shaft 5 and is rotatable with respect thereto. A tension spring 20 is provided for normally holding the actuating member 16 in its rotative position with respect to the rotating member 8. An annular footrest 21 is carried by the rotating member 8 and positioned beneath the seat portion 9.

From the foregoing description of the various parts of the device, the operation thereof may be readily understood. Any number of persons that may sit upon the seat portion 9 may actuate the device. To start the member 8 rotating, the person sitting at the point indicated at X would push upon the actuating member 16 and the person sitting at the position indicated at Y would pull upon the actuating member 16. In this manner the rotating member 8 would start rotating in a clockwise direction.

The person sitting upon the seat portion 9 could continue and increase the rotative motion of the member 8 by pushing and pulling upon the actuating member 16. The actuating member 16 will rotate with the rotating member 8 but about a different center. This different center enables the device to be readily actuated. As the member 8 is rotated, it is supported by the shaft 5, but does not rotate about the center of the shaft. Therefore, there is an oscillatory movement as well as a rotative movement of the actuating member 16.

It may be observed that the device has only two movable parts; namely, the rotating member 8 and the actuating member 16. Furthermore, the device may be actuated not only by the pulling of one person upon one side and the pushing by another person directly opposite, but it may be actuated during the rotative movement thereof by all the

persons seated thereupon with the exception of the two persons who are seated opposite the vertical shaft 5 when the actuating device is at dead center. By viewing Figure 2, it will be noted that the dead center line is directly across the horizontal center line of the device. Therefore, any persons seated around the device, with the exception of the two points upon the horizontal center line, may, while the device is in this position, aid in actuating the device. The point is that all persons may at all times during the revolution of the device aid in actuating the device with the exception of the two times when they are positioned directly at the dead center points. Furthermore, in view of this fact, the device may readily be stopped and readily rotated in the opposite direction.

I claim:

1. A device of the kind described embodying therein a base, an annular member on said base, an upright member arranged eccentrically of said annular member, a seating means supported on said upright member for rotation concentric with respect to said annular member, means carried by said seating means for a guiding engagement with the periphery of said annular member and an actuating member rotative on said upright member but eccentric with respect to said seating member.

2. A device of the kind described embodying therein a base, an annular member on said base, an upright member arranged eccentrically of said annular member, a seating means supported on said upright member for rotation concentric with respect to said annular member, means carried by said seating means for a guiding engagement with the periphery of said annular member, a tube rotative about said upright member and an actuating member fixed to said tube and positioned for convenient grasping from said seating means.

3. A device of the kind described embodying therein a base, an annular member on said base, an upright member on said base arranged eccentric with respect to said annular member, an annular seat concentric with said annular member and supported by said upright member, rollers on said annular seat having peripheral engagement with said annular member and an annular actuating member rotative about and supported by said upright member.

4. A device of the kind described embodying therein a base, an annular member on said base, an upright member on said base arranged eccentric with respect to said annular member, an annular seat concentric with said annular member and supported by said upright member, rollers on said annular seat having peripheral engagement with said annular member and an annular actuating member rotative about and supported by

said upright member and a spring connecting said actuating member with said annular seat.

5. A device of the kind described embodying therein a base, an annular member fixed to said base, an upright member fixed to said base and extending through said annular member but off center thereof, an annular seat arranged concentric with respect to said annular member, a cap member pivotally mounted on said upright member concentric with said annular member, arms connecting said seat and cap members, other arms extending inwardly from the seat member and carrying rollers for peripheral guiding engagement with said annular member and an annular actuating member rotative about and supported by said upright member.

Signed at Menominee in the county of Menominee and State of Michigan this 18th day of January A. D. one thousand nine hundred and twenty-nine.
